UNITED STATES PATENT OFFICE.

WILLIAM VAN DEN HEUVEL, OF LOS ANGELES, CALIFORNIA.

CABLEWAY.

1,362,275.

Specification of Letters Patent.

Patented Dec. 14, 1920.

Application filed April 9, 1919. Serial No. 288,810.

To all whom it may concern:

Be it known that I, WILLIAM VAN DEN HEUVEL, a subject of Holland, residing at Los Angeles, in the county of Los Angeles, 5 State of California, have invented new and useful Improvements in Cableways, of which the following is a specification.

This invention relates to cableway systems and, although not limited in its particular 10 construction to or use to a cableway excavator, it is particularly adapted to cableway excavators of the class herein described. An object of the invention, as applied generally to cableways, or specifically as applied to 15 cableway excavators and the like, is to facilitate the efficient operation of such cableway or cableway excavators, and to increase the safety of their operation.

Heretofore it has been more or less common in cableway structures of the general character herein described to employ a head tower of sufficient height and suspend a track cable from this head tower to a foot anchorage of some character. This foot anchorage 20 may be either fixed or movable and where the foot anchorage is movable it has been more or less common to provide a swiveling structure on the head tower so as to keep the track cable connection, etc. on that tower turned 25 in its proper relative disposition to the foot anchorage. It has been more or less common to put a swiveling or turntable platform in the upper part of the head tower and on this platform to mount the hoist or hoists 30 or other mechanisms which are used to take up and pay out slack in the track cable and to operate the excavating bucket or other traveling element along the track cable. Such a construction requires a tower of weight and 35 strength greatly in excess of what is needed in my improved design, and requires bracing of the tower in all directions.

Furthermore, in such constructions, failures have been frequent in the operating cables which are used to let out and take up slack on the track cable; and any breakage or failure in the slack adjusting system of course has allowed the track cable to be immediately released, usually with disastrous 45 results. In installations of the character here described, where the head tower may be 100 feet or more in height, and where the span covered by the track cable may be a thousand feet or more, the strain upon the 50 track cable, when the bucket or other traveling element is being operated, is very great.

Under this great strain, if the means for holding the end of the track cable gives way, the track cable is released under an enormous 60 force, usually causing a great deal of damage in addition to causing inevitable delay in getting the apparatus in working order again.

My new design and arrangement overcomes these difficulties, as well as various 65 other minor difficulties in the present construction. I provide a head tower designed and constructed to give its maximum effective strength to resist forces imposed upon it by the track cable, and the other operating 70 cables and parts, substantially in a single direction, or in directions within a comparatively small angle; and then I preferably make this tower so that, as a whole, it is movable to be adjusted and put in proper 75 position to effectively face the foot anchorage in its different positions of adjustment or movement. Then I provide a slack controlling system for the track cable which system includes a slack controlling device 80 operative in such a manner as to control the paying out of slack upon the track cable and also as to control and effectively hold the track cable in case of breakage or failure 85 of any kind in the mechanism by which the slack is adjusted. I provide an arrangement of the various parts of the whole combination such that, where the head tower is movable, it is movable as a whole and the hoist and slack controlling mechanisms move 90 with it without changing relative position. I hereinafter explain a head tower which is 95 rotatively movable; but it will be understood that the tower and its accompanying parts may be moved in any desired manner. These and other general features of my invention, together with other features of more or less specific detail, will be best understood, and the invention as a whole will be most easily intelligible, from the following 100 detailed description of preferred forms of systems and devices embodying my invention, reference for this purpose being had to the accompanying drawings, in which—

Figure 1 is an elevation showing the general lay-out of my system; Fig. 2 is a corresponding plan; Fig. 3 is an enlarged detail view taken as indicated by line 3—3 on Fig. 2; Fig. 4 is an enlarged detail view taken as indicated by line 4—4 on Fig. 2; Fig. 5 is an enlarged elevation of the slack adjusting mechanism; Fig. 6 is an elevation

of the same taken as indicated by line 6—6 on Fig. 5; Fig. 7 is an enlarged detail section taken as indicated by line 7—7 on Fig. 6; and Fig. 8 is a view similar to Fig. 1, illustrating a modified form and arrangement of the system.

In the drawings a head tower is shown at A and a tail tower at F. These two are spaced apart a suitable distance, depending upon the extent of excavation or other work desired; and a track cable C is suspended between them. In the arrangement shown in Figs. 1 and 2, the track cable is permanently anchored at 10 to the tail anchorage and also permanently anchored at 11 to the head tower; the slack in the cable being changed and adjusted by movement of the head tower. The head tower is preferably formed of a pair of forward legs 12, each of which is pivoted at 13 on a small carrying truck 14 running on rails 15 as illustrated. In the form and arrangement herein shown and described this head tower is made to be adjustable in position, as a whole, by swinging around the vertical center designated C¹ in Fig. 1. A rear strut 20 is pivotally connected at 21 to the top of the legs 12 of the head tower; and this strut 20 is normally in tension, for the cable C delivers a strain or force to the top of the head tower, which tends at all times to pull the front legs 12 forwardly. At E there is an extensible and contractible mechanism which, as a matter of structure, can be taken as forming a contractible and expanding part or element of the strut 20; and it is in this mechanism, and in its combination with the other parts herein described, that some of the features of my invention reside. Referring particularly to Figs. 5 and 6, I will now explain in detail one preferred form of this mechanism E. I preferably use a cylinder of a proper length; the length depending upon the amount of expansion and contraction desired in order to throw the front legs 12 of the tower back and forth through a sufficient variation to give to track cable C the differences in slack required in operation. Such a cylinder is shown at 25; and the upper end of this cylinder is directly connected at 26 with the lower end of the tension strut 20, so that the cylinder moves with the strut. A piston 27 is mounted in the cylinder and the piston rod 28 is connected at 29 to a pivot 29^a mounted in a foot bracket 30; this pivotal mounting providing for the swinging motion of the mechanism E and the strut 20. The strut 20 with its mechanism E form a stiff member which is sufficiently strong in compression to support the dead weight of the tower when the tension of cable C is relieved. Normally this member is a tension strut. Foot bracket 30 is mounted on a vertical pivot 31 on a base 32; and bolts

are provided at 33 to set and hold the foot bracket 30 in any desired position. When the head tower is swung around to any set position, the mechanism E and the foot bracket 30 are also swung around and are then set rigidly into position by tightening the bolts 33. The foot bracket 30 may carry the platform P on which the hoist H may be mounted. This hoist, which may be of any desired character, and operated by any suitable motive power, winds up or pays out simultaneously upon two ends of a cable 35. This cable 35 (to describe its passage in sequence from one end to another) passes from the drum of the hoist under a sheave 36 at one side on the pivot shaft 29^a and then passes upwardly and over the sheave 37 mounted on a shaft 38 which is mounted and carried in the upper part of the structure of cylinder 25; and then passes down and around and under another sheave 36 on shaft 29^a and then up and over a sheave 38 which is mounted on cylinder 25; thence downwardly again and under and around another sheave 39 on shaft 29^a, arranged on the side of the machine opposite to the side on which sheaves 36 are arranged, and thence upwardly and over another sheave 37 at the top of the cylinder and thence downwardly and under another sheave 39 and back to the drum of the hoist. It will be seen that rotation of the hoist drum in one direction causes the two ends of the cable to be wound up on it causing the upper part of the mechanism E—the element of the mechanism which comprises the cylinder and the parts mounted upon it—to be drawn downwardly. Rotation of the hoist drum in the opposite direction, will allow the cable to unwind from the hoist and will allow upward movement of the cylinder and the parts connected with it.

The mechanism E and the hoist H are mounted upon a suitable foundation D which is anchored in any suitable manner to resist the upward strains imposed on it.

The two ends of cylinder 25 are connected by pipes 40, 41 and 42, with a valve interposed at 43. This valve may be opened and closed in accordance with the operation desired, or may be set in an adjusted position to pass the fluid, preferably oil, at a restricted rate. If any of the operating parts, such as a cable 35 or the hoist mechanism, should break or give way in any manner, it will readily be seen that the tower will not be, by that fact, suddenly and freely relieved; but the restriction against the flow of fluid from one end of cylinder 25 to the other will cause the mechanism E to only gradually and slowly expand in length, so that, under such circumstances, the track cable C will be gradually slackened until the limit of expansive movement in mechanism E is reached. When this is

done of course a great deal of strain has been relieved from the head tower, because the maximum amount of slack has been paid out onto the track cable C; and the piston 5 27 will bring up against the end of the cylinder relatively easily. Thus all sudden shock, with its resultant damage, is easily obviated. The structural parts of mechanism E are made strong enough to with- 10 stand, with an ample factor of safety, all the strains that may at any time be put upon it; so the mechanism E becomes in fact a safety control; or a compensator for the cable tension to cause retarded movement in the case 15 of accident. Of course this same element causes retarded movement in ordinary operation. For instance, in letting out slack, it is only necessary to release the brake B of the hoist mechanism and allow the mecha- 20 nism E to be extended under the strain imposed upon the tower by the track cable, until the desired amount of slack has been paid out into the track cable, when the brake may be again applied. The brake need not 25 be used to retard the paying out of slack. Or this paying out of slack may be entirely controlled with the valve 43; the valve being opened to allow passage of fluid at a suitable speed, and closed when the desired 30 position is obtained. Various other methods of manipulation, by the combined use of the hoist operated cables and the valve 43 will readily occur to those skilled in the handling of such machinery, and need not be 35 described here. However, it may be mentioned that fluid pressure may be introduced say, through a pipe 50, and may be diverted, by the manipulation of valves 51, through pipes 52 and 53, to either end of the cyl- 40 inder, to cause or to assist in causing movement of the piston in the cylinder by reason of fluid pressure; provision being made through the medium of valves 54, for allowing escape of fluid from one end of the cyl- 45 inder when fluid is being forced into the other end. Such fluid pressure operation of the mechanism E may entirely take the place of the cable and hoist operation of the same. But at the same time, it will be seen, 50 the by-pass plays its part and will always act to prevent too fast movement of the parts if the operating means should give way. For instance, if the pressure in the lower part of the cylinder should suddenly 55 be relieved, valve 51 can be closed and the by-pass valve 43 will then take care of the movement. Or valve 51 (the valve through which fluid pressure is admitted to the lower end of the cylinder) may be set so as to 60 allow passage of fluid only at a restricted rate; and then any breakage in the fluid pressure system exterior to valve 51 will simply have the effect of allowing fluid to escape slowly from the cylinder, allowing 65 the track cable to be slackened slowly. By

such use of the fluid pressure connections for fluid operation, it will be seen that the emergency movement retarding means may be included in the means for operating the mechanism E, or may be independent of it— 70 where by-pass valve 51 is used exclusively to retard the movement. For the purpose of quickly and automatically closing the passage of liquid through valves 51; in case of a break in the pressure system connected 75 to pipe 50, check valves 51^a may be installed which open in the directions indicated by the arrows.

The tail anchorage at F is preferably made in the form of a counterbalanced truss. 80 The forward end of this truss travels on a track T which may consist of a single rail laid on sleepers S on a curve concentric about the center C¹. The truss has spaced wheel bearings at 60 on the rail T; and the 85 truss is preferably formed as illustrated in the drawings, the track cable C being connected to its uppermost point, about central of the truss. The rear end of the truss, which is brought down to a pointed construction, which is illustrated at 61, is loosely connected (as by a pair of loose shackle bolts shown at 62) to a car 63 which runs upon a track T¹. This car is weighted with any suitable material; and the weight 90 of the car is sufficient at all times to keep the truss down in its proper position, the moment exerted by the weighted car upon the truss with respect to the center of rotation of the truss upon the track T being 95 greater than that exerted by the track cable C upon the truss with respect to that center. Because the connection at 62 between the truss and the car is a loose connection, it will be seen that track T¹ need not be laid with 100 any great accuracy; a general parallelism of track T¹ to track T being sufficient.

The tracks T and T¹ may be of any desired extent and may extend more or less completely in a circle around the center C¹. 110 The tail anchorage F is of course placed in position to put the track cable C wherever desired; and the head tower A is put into a corresponding position. Now it will be noted that head tower A is so constructed 115 that it is of maximum efficiency, as regards strength, when it is facing the foot anchorage F; and the head tower A may be adjusted in position to keep substantially at all times this position facing the tail an- 120 chorage F. Of course this does not mean that the vertical plane of the track cable C must at all times accurately bisect the angle between the two front struts 12—there can be some substantial variation from this 125 theoretically best position, the amount of variation depending upon the angle be- between the front struts 12. But it is designed to keep the head tower in substantially this relative position, faced toward the tail 130

anchorage. The head tower being designed for maximum strength to resist strains imposed upon it in substantially one direction only, it is readily seen that there is no waste 5 of material, or excess weight, in the tower.

Although I for some reasons prefer the form and arrangement which has been described, particularly because in large installations a "locked cable" may be used as a 10 track cable, the cable not having to pass over a sheave but being directly secured to the tower; yet my invention may be applied to other forms and arrangements. In Figs. 15 1 and 2 I have illustrated the track cable 15 as being permanently attached to the top of the head tower A; and have illustrated and described the arrangement and method of changing the slack by means of moving the head tower itself. In Fig. 8 I show an arrangement 20 wherein the head tower A¹ is not adjustable in position with regard to movement in a vertical plane (although of course it may be movable horizontally as a whole, or adjustable rotatably about a vertical axis as has been hereinbefore described). This tower may be supported permanently in position by a rear supporting strut 20¹; and the track cable C passes over a large sheave 70 at the upper end of the 25 tower; the track cable extending downwardly and being connected to the expansive and contractive mechanism E which is the same as hereinbefore described. The operation of mechanism E is the same as hereinbefore stated; except that in this case it of course takes in and pays out slack directly upon the cable C, without moving the head tower. Outside of this distinction however, 30 the two systems are the same. And it will be readily understood from this how my invention 35 may be applied to other variations and to other systems with equal effect.

In the form of device shown in Fig. 1 where the head tower is rotated or otherwise 40 movable as a whole in order to be adjusted in position, I may tie the lower ends of the forward legs 12 with a connective tie beam 70. The platform P which carries the hoist H and also carries the hoist H¹ operating 45 cable 72 to operate the excavator or other traveler 73—this platform P may be mounted upon or connected to the rotatable foot bracket 30 in any suitable manner such as shown in detail in the drawings. There 50 may also be ties 74 between this platform and the lower ends of the forward struts or legs 12. By this sort of construction the three strut or leg elements of the tower are 55 horizontally tied together at their lower ends; so that all the parts may be easily moved together with one another, and so that no spreading strains are put upon the track 15 and so that it is unnecessary to lock the trucks 14 to the track as rigidly or 60 as strongly as would otherwise be necessary 65

to hold the lower ends of the front legs 12 in proper position and keep these legs from spreading apart. It is to be noted however, that the track 15 is placed at such an angle 70 that the thrust of legs 12 through the trucks 75 and on to the track is substantially at right angles to the plane of the track. This is strictly true when the tower legs are in their medial position (the tower as shown in Fig. 1 in its position substantially farthest to the left; or in the position where the track cable C is held at its greatest tension).

In the form shown in Fig. 8, which illustrates a non-moving tower structure, it is of course, not necessary to have the horizontal 80 ties, as each of the three vertical strut or leg members is mounted directly upon a permanent foundation. In this case the two hoists are also mounted upon permanent foundations.

Now whether both of the hoists (or the hoist H¹ and, broadly speaking, the means for operating the mechanism E) are mounted upon a platform rotative upon a foundation or are mounted directly upon a permanent foundation, there are peculiarly advantageous features of operation in my structure which are not found in any present structures of which I am aware. In most present structures the hoist mechanism 95 which operates the traveler is mounted upon a rotative platform at the top of the heavy tower structure hereinbefore referred to. The track cable runs over a sheave supported on this rotative platform. Foundations or 100 anchors known as "dead-men" are placed behind the tower and the follower block apparatus is anchored to these dead-men and attached to the track cable. The hoist mechanism which operates the follower block is 105 then mounted on a suitable permanent foundation behind the tower. Even in such a construction as this where the direct lineal pull of the track cable is resisted by the rear anchorages there is of course in every case a 110 tendency on the part of this cable tension to pull the tower forward, due to the fact that the cable passes over and down behind a sheave at the top of the tower. When the traveler hoist is mounted, as it is, on a platform at the top of the tower, all the horizontal strains of operating the traveler along the tower cable are transmitted wholly to the tower and tend to pull the tower forwardly. In other words these strains have 115 cumulative effect with the strains of the track cable tending to pull the tower forwardly at its top; and this is one of the reasons why such towers have been heretofore constructed with such excessive bulk 120 and heaviness.

On the other hand, in my construction it will be seen that the direct lineal strain on the traveler cable is transmitted down to the hoist which is mounted on a foundation; 130

consequently these strains tend somewhat to hold the tower down instead of being effective solely and wholly toward overturning the tower.

- 5 In the movable form of my device where the hoist moves, or rotates, with the tower as a whole it will be seen that the hoists and the slack mechanism and all other parts are always in proper working relation to the tower. It is not necessary, as has herebefore been the case, to change the position of the hoist, etc. every time the position of the tower has to be changed slightly. This fact not only facilitates changing the position of 10 my apparatus and makes it very easy to handle as compared with prior structures; but this easy adjustment is also a very great inducement to the operator's keeping the head tower in true alinement at all times; and this is a feature of considerable practicable importance in a movable tower construction and especially in my design where the tower is designed and constructed for maximum efficiency in a single direction of 20 operation.

Having described a preferred form of my invention, I claim:

1. In a cableway, a suspended cable, means for selectively varying the slack on said cable, and movement retarding means connected with the cable, said retarding means operating to insure a gradual taking up of slack by said cable when varied by said varying means.
- 35 2. In a cableway, a suspended cable, means for varying the slack on said cable, and movement retarding means connected with the cable to take the strain of the suspended cable in case the slack varying means 40 gives way.

3. In a cableway, a tower, a cable connected to the tower, means for selectively varying the slack on said cable by moving the tower, and movement retarding means 45 connected to the tower to insure a gradual movement of the same.

4. In a device of the character described, a slack controlling mechanism, embodying two relatively movable elements, one of 50 said elements being connected to a cable, means to cause relative movement of the elements to vary the slack in the cable, and movement retarding means between the two elements.

- 55 5. In a device of the character described, a slack controlling mechanism, embodying two relatively movable elements, one of said elements being connected to a cable, means to cause relative movement of the elements 60 in one direction to take up slack in the cable, and means to retard relative movement of the elements in the opposite direction.

6. In combination with a suspended cable, a slack controlling mechanism embodying

two elements one connected to the cable and the other relatively fixed, means for relatively moving said elements to take up slack in the cable, and motion retarding means between the two elements.

7. In combination with a suspended cable, 70 a slack controlling mechanism embodying two elements one connected to the cable and the other relatively fixed, means for relatively moving said elements to take up slack in the cable, and motion retarding means between the two elements to retard motion thereof in a direction to pay out slack in the cable, said retarding means being independent of the motion causing means.

8. In combination with a suspended cable, 80 a slack controlling mechanism embodying two elements one connected to the cable and the other relatively fixed, means for relatively moving said elements to take up slack in the cable, and motion retarding means between the two elements to retard motion of the elements opposite to that caused by the first mentioned means.

9. In combination with a suspended cable, 90 a slack controlling mechanism embodying two elements one connected to the cable and the other relatively fixed, means for moving said element which is connected to the cable, in one direction to take up slack in the cable, and fluid pressure means for retarding motion between the two elements.

10. In combination with a suspended cable, a slack controlling mechanism embodying two elements one connected to the cable and the other relatively fixed, means 100 for moving said element, which is connected to the cable, in one direction to take up slack in the cable, and hydraulic means for retarding motion between the two elements in a direction opposite to that caused by the 105 hoist and cable.

11. In combination with a suspended cable, a slack controlling mechanism embodying two elements one connected to the cable and the other relatively fixed, said two 110 elements including respectively a cylinder and a piston, fluid pressure means for operating the piston in the cylinder, and means for retarding the movement of the piston in the cylinder embodying a means for restricting the passage of fluid from the cylinder.

12. In a device of the character described, a slack controlling mechanism, embodying two relatively movable elements which include respectively a piston and a cylinder, said cylinder adapted to contain a fluid, a controllable by-pass between the ends of the cylinder to control and retard movements of the piston, and independent means for causing relative movement of the two elements.

13. In a device of the character described, a slack controlling mechanism, embodying

two relatively movable elements which include respectively a piston and a cylinder, said cylinder adapted to contain a fluid, a controllable by-pass between the ends of the 5 cylinder to control and retard movements of the piston, and fluid pressure means to move the piston in the cylinder.

14. In a device of the character described, a slack controlling mechanism embodying 10 two relatively movable elements which include respectively a piston and a cylinder, said cylinder adapted to contain a fluid, a controllable by-pass between the ends of the cylinder to control and retard movements of the piston, and independent means for causing movement of the two elements toward 15 each other so as to contract the mechanism.

15. In a device of the character described, a slack controlling mechanism, embodying 20 two relatively movable elements which include respectively a piston and a cylinder, said cylinder adapted to contain a fluid, a controllable by-pass between the ends of the cylinder to control and retard movements of 25 the piston, sheaves carried by the two elements, a cable passing over said sheaves, and means to take up and pay out the cable.

16. In a device of the character described, a tower embodying front legs pivotally 30 mounted at their lower ends and joined at their upper ends, a strut member standing behind the legs, said member including an expansive and contractive mechanism, and means to contract and expand such mechanism and thereby to expand or contract the 35 effective length of the rear strut member.

17. In a device of the character described, a tower embodying spreading front legs and a strut member standing behind the legs, a 40 track cable supported by the tower, and a mechanism adapted to pay out and take up slack on the track cable, the tower as a whole and said mechanism being mounted movably to be moved together in fixed relative position.

18. In a device of the character described, a tower embodying spreading front legs and a strut member standing behind the legs, a track cable supported by the tower, and a 50 mechanism adapted to pay out and take up slack on the track cable, a traveler on the track cable and a cable for the traveler passing over the tower, a hoist to operate said cable, and the tower as a whole and said mechanism and the hoist being mounted to be movable together in fixed relative position.

19. In a cableway, the combination of a head tower, a foot tower, a track cable suspended 60 between them, the foot tower being movable and the head tower being movable as a whole to adjust its position with relation to the foot tower, a traveler and a traveler cable passing over the head tower,

and a hoist for the traveler cable mounted 65 on a foundation below the tower so that the strains of the traveler cable are transmitted through the hoist to the foundation.

20. In a cableway, the combination of a head tower, a foot tower, a track cable suspended 70 between them, the foot tower being movable and the head tower being movable as a whole to adjust its position with relation to the foot tower, a traveler and a traveler cable passing over the head tower, and a hoist for the traveler cable mounted on a 75 foundation below the tower so that the strains of the traveler cable are transmitted through the hoist to the foundation, and said hoist being movable on its foundation 80 with the tower as to maintain a fixed relation to it.

21. In a device of the character described, a tower embodying a pair of forward spreading legs and a rear tension strut 85 member which includes a contractive and expansive mechanism, the forward legs being pivotally mounted at their lower ends and the rear strut being pivotally connected to the upper ends of the forward legs, so that 90 expansion and contraction of said mechanism will cause change of position of the forward legs.

22. In a device of the character described, a tower embodying a pair of forward 95 spreading legs and a rear tension strut member which includes a contractive and expansive mechanism, the forward legs being pivotally mounted at their lower ends and the rear strut being pivotally connected to the 100 upper ends of the forward legs, so that expansion and contraction of said mechanism will cause change of position of the forward legs, and a movable mounting for all the foregoing named parts whereby they 105 may be moved together in fixed relation to each other.

23. In a device of the character described, a tower embodying a pair of forward spreading legs and a rear tension strut member 110 which includes a contractive and expansive mechanism, the forward legs being pivotally mounted at their lower ends and the rear strut being pivotally connected to the upper ends of the forward legs, so that expansion and contraction of said mechanism 115 will cause change of position of the forward legs, and a mounting for all the foregoing named parts whereby they may be all swung together around a center point near the lower 120 end of the rear strut.

24. In a device of the character described, a tower embodying a pair of forward spreading legs and a rear tension strut including a contractive and expansive mechanism, mountings for the forward legs which 125 include pivotal supports for the legs and means whereby the legs may be moved in

circular movement about a center substantially co-incident with the lower end of the rear strut, a pivoted foot bracket to which the lower end of said strut is pivoted, a platform mounted to swing with the foot bracket about its pivot, and means on the platform for causing operative change of length of the said mechanism to cause change of effective length of the strut to

thereby tilt the legs about their lower pivotal mountings.

In witness that I claim the foregoing I have hereunto subscribed my name this 31st day of March, 1919.

WILLIAM VAN DEN HEUVEL.

Witness:

VIRGINIA BERNINGER.
